SHOE-LAST

Filed Feb. 11, 1944

INVENTOR:
CHARLES W. MARCILLE,

By *Raymond H. Smith*
ATTORNEY.

UNITED STATES PATENT OFFICE

2,392,826

SHOE LAST

Charles W. Marcille, St. Louis, Mo.

Application February 11, 1944, Serial No. 521,897

8 Claims. (Cl. 12—136)

This invention relates to a certain new and useful improvement in shoe-lasts.

My invention has for its chief object the provision of a last comprising companion members uniquely joined for convenient insertion into and removal from the shoe-body without subjecting the shoe-body to strain or stretching at any point during such operations.

My invention has for a further object to obviate last breakage and loss and, to such end, the provision of a last having its complementary members not only uniquely joined for ready insertion into and removal from the shoe-body, but also efficiently re-enforced against breakage during the shoe making.

My invention has for another object the provision of a shoe-last of the type stated which may be readily constructed, which is sturdy and reliable, which is conveniently usable, and which is efficient in the performance of its intended functions.

And with the above and other objects in view, my invention resides in the novel features of form, construction, arrangement, and combination of parts presently described and pointed out in the claims.

In the accompanying drawing:

Figure 1 is a side elevational view of a last constructed in accordance with, and embodying, my present invention, the companion or complementary body-members of the last being in abutting engagement or co-operation as when in shoe-lasting position;

Figure 2 is a similar view of the last in so-called broken condition, the complementary body-members of the last being hingedly spaced and the last correspondingly shortened for facilitating insertion and removal thereof into or from the particular shoe-body;

Figure 3 is an enlarged fragmental sectional view of the last with its body-members in lasting position, as in Figure 1;

Figure 4 is a similar view of the last with its body-members in last-shortening position;

Figure 5 is a detail fragmental sectional view of the last taken approximately on the line 5—5, Figure 3; and

Figures 6 and 7 are perspective views of housed plate-sections co-operable with the complementary body-members of the last for facilitating their relative movement to and from, and retention in, lasting position.

Referring now more in detail and by reference characters to the accompanying drawing, which illustrates a preferred embodiment of my invention, the last, as is common in the industry, includes companion or complementary so-called fore or vamp and rear or heel sections A and B, respectively, constructed preferably of suitable wood and of combined selective contour and shoe-

size or dimensions, as will be understood, the last being also, as is customary, initially in a unitary body and then obliquely downwardly and rearwardly split and shouldered and thereby divided to include the companion members A and B having matching rear and front faces 1, 2, respectively, and also matching opposed shoulders 3, 4, respectively.

Forwardly from its rear face 1, the last body-member A is cut away and thereby provided with a recess or chamber 5 opening rearwardly upon said face 1, and rearwardly from its front face 2, the last body-member B is likewise cut away and thereby provided with a companion recess or chamber 6 opening forwardly upon said face 2, the chambers 5 and 6 having preferably the contours and relative locations best seen in Figures 3 and 4.

C designates a rigid, sturdy, preferably metallic plate-section contoured preferably as best seen in Figure 6 and, for purposes presently appearing, provided with transverse openings 7, 8, and 9, and D designates a preferably metallic link contoured preferably as best seen in Figure 7 and, also for purposes presently appearing, provided transversely with a slot 10 and an opening 11.

The plate-section C is for the most part located, and as by means of transverse pins 12 and 13 fixed in the last body-member A and extending through said openings 7 and 8, reinforcingly secured within the chamber 5, the plate-section C having, as shown, a tail-extension c projecting rearwardly to generally reside within the recess 6 of last-member B.

The link D is for the most part located, and by means of a pin 14 transversely fixed in the last body-member B and projecting through said slot 10, pivotally secured for movement within the last-body recess 6, the link D having a nose-extension d projecting forwardly to generally reside and work in the recess 5 and the link D, as its said extension d, being hingedly, as by means of a stud or rivet 15 suitably fitted in the companion or registering openings 9, 11, attached to the plate C for securing the last-members A and B swingably together. And it may be here stated that the link D is formed on the front wall of its nose-extension d with a pocket, as at 16, for engaging the fixed pin 13 when the last-members A and B are in abutting shoe-lasting position, as in Figure 1.

Suitably formed and located in the rear face or margin of the fixed plate C, is a recess or socket, as at 17, to receive the lower or outer end of the shank e of a pin E lengthwise shiftable in and through the apertured end wall f of a cup F fixed in the shoulder b of the last-member B for shiftably retaining the last-body-members A and B in abutting shoe-lasting position, as in Figure 1, the pin E being yieldingly urged or

biased in its engagement with the pocket 17 as by means of a spring 18 coiled on the shank e intermediate a shank collar 19 and an apertured nut-member 20 thread-seated about the shank e in the cup F, all as best seen in Figures 3 and 4.

So constructed, in use and operation, on the pin E being yieldingly retracted from engagement with the last-body-member A at its socket 17, the last-body-members A and B may be readily pivotally shifted relatively to each other for breaking and lengthwise shortening the last, as shown in Figure 2, for facilitating either placement of the last within the shoe-body to be lasted or removal of the last from the lasted shoe, the link D in so shortening the last pivotally at its nose d and pocket 16 moving away from the pin 13, as indicated or shown in Figure 4. On reversely relatively shifting the hingedly link-connected members A and B, the members A and B return to their relative abutting engagement, as in Figure 1, when the pin E springs into engagement at its shank e with the recess or pocket 17 and the link D re-engages at its nose d and pocket 16 with the stud 13, the last-body-members A and B being thereby retained with firmness and rigidity in abutting shoe-lasting position, the fixed plate C largely, when the last-body-members A and B are in such shoe-lasting position, taking the pull of the pin E and link D from, and thereby most efficiently reenforcing against breakage, the last-member A.

The last fulfills in every respect the objects stated, and it is to be understood that changes and modifications in the form, construction, arrangement, and combination of the several parts of the shoe-last may be made and substituted for those herein shown and described without departing from the nature and principle of my invention.

Having thus described my invention, what I claim and desire to secure by Letters Patent is:

1. A shoe-last including a pair of complementary body-members adapted for endwise registration and abutment when in shoe-lasting position, said members being co-operably recessed in their opposing end faces, means comprising a link for joining said body-members swingably together, and a stud fixed in one of the body-members and engageable by the link when said members are in shoe-lasting position.

2. A shoe-last including a pair of complementary body-members adapted for endwise registration and abutment when in shoe-lasting position, said members being co-operably recessed in their opposing end faces, a plate-section disposed within the recess of one body-member, a stud engaging said plate-section and said one body-member, and a link pivotally attached to said plate and to, and within the recess of, the other plate and engageable with the stud when said members are in shoe-lasting position.

3. A shoe-last including a pair of complementary body-members adapted for endwise registration and abutment when in shoe-lasting position, said members being co-operably recessed in their opposing end faces, a plate-section, means comprising a stud engaging said plate-section and one body-member for securing said plate partially within the recess of said one body-member and partially in the recess of the other body-member, and a link pivotally attached to

said plate and to the other body-member, the link being disposed for movement in said recesses and having a nose-extension having a pocket for engaging said stud when said members are in shoe-lasting position.

4. A shoe-last including front and rear complementary body-members adapted for endwise registration and abutment when in shoe-lasting position, said members being co-operatively recessed in their opposing end faces, means comprising a plate fixed in one of said members for joining the members swingably together, said plate having a marginal recess, and means comprising a pin biased in the other member for engagement at its shank in said recess for yieldingly securing said members in shoe-lasting position.

5. A shoe-last including a pair of complementary body-members adapted for endwise registration and abutment when in shoe-lasting position, said members being co-operably recessed in their opposing end faces, a plate-section, means comprising a stud engaging said plate-section and one body-member for securing said plate partially within the recess of said one body-member and partially in the recess of the other body-member, a link pivotally attached to said plate and to the other body-member, the link being disposed for movement in said recesses and having a nose-extension having a pocket for engaging said stud when said members are in shoe-lasting position, and means for retaining said body-members in shoe-lasting position.

6. A shoe-last including front and rear complementary body-members adapted for endwise registration and abutment when in shoe-lasting position, said members having complementary recesses in their opposing end faces, a plate fixed in one of said members and a link pivotally secured in the other member, said plate and link being, in turn, pivotally secured together at a point disposed upwardly in relation to the point at which the link is secured to said other member when the last is in shoe-lasting position.

7. A shoe-last including front and rear complementary body-members adapted for endwise registration and abutment when in shoe-lasting position, said members having complementary recesses in their opposing end faces, a plate fixed in one recess and having an abutment member associated therewith, and a link pivotally mounted upon the plate upwardly from the abutment member with respect to the sole of the last, said link being provided with a slot through which it is shiftably and pivotally secured within the other recess also at a point which is disposed below the pivot-point between the plate and link when the last is in shoe-lasting position.

8. A shoe-last including a pair of complementary body-members adapted for endwise registration and abutment when in shoe-lasting position, said members having co-operable recesses in their opposing end faces, a plate-section disposed partially within the recess of said body-member, a stud also disposed in the recess of said body-member, a link pivotally attached to said plate and to, and within the recess of, the other body-member, the link having abutment means for engaging said stud when said members are in shoe-lasting position.

CHARLES W. MARCILLE.
